UNITED STATES PATENT OFFICE.

THOMAS J. SHEA, OF PORTLAND, OREGON.

BOILER.

1,157,813.

Specification of Letters Patent.

Patented Oct. 26, 1915.

Application filed February 13, 1914. Serial No. 818,460.

To all whom it may concern:

Be it known that I, THOMAS J. SHEA, a citizen of the United States, and a resident of Portland, in the county of Multnomah and State of Oregon, have invented a certain new and useful Boiler; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to boilers, and particularly to boilers of the vertical type, commonly known in some localities as "donkey boilers," and combining both water tubes and fire tubes in their construction.

The object of my invention is the provision of an improved boiler of the character described, which is particularly designed for use in logging camps, but is not restricted to such use, and is capable of having oil, wood or coal used as fuel therein, and also of being easily transported from one place to another.

The invention is fully described in the following specification, and while, in its broader aspect, it is capable of embodiment in numerous forms, a preferred embodiment thereof is illustrated in the accompanying drawings, in which,—

Figure 1 is a central vertical section of a boiler embodying the invention taken through the fire door. Figs. 2 and 3 are cross-sections thereof on the lines $x-x$ and $y-y$ in Fig. 1, with the water tubes in the latter removed, and Fig. 4 is a partial cross-section on the line $z-z$ in Fig. 1.

Referring to the drawings, 1 and 2 designate the inner and outer shells of a boiler, which may be of any suitable size or shape in cross-section and have their side walls held in rigidly spaced relation by stays 3, or in any other suitable manner, to provide the water-leg space 4 therebetween. The inner shell 1 forms the fire-box of the boiler and is provided adjacent to the lower end 50 of the outer shell with an inturned ledge 5 which terminates at its inner edge in a downwardly projecting flange 6 forming an opening 7 in the bottom of the fire-box, which is of less diameter than the diameter 55 of the fire-box and may have the customary grate 8 disposed therein if wood, coal or

other ash-producing fuel is used. The opening 7 is intended to communicate at its lower end with an ash-pit (not shown), such ash-pit being customarily provided in the base 60 upon which the boiler is mounted. The lower edges of the outer shell 2 and flange 6 are connected by a flange 9 of annular or other suitable form conforming to the bottom shape of the boiler. The ledge 5, flange 65 6 and bottom plate 9 coöperate to form an enlarged water space at the base of the water-leg 4, such space extending inward under the marginal edge portion of the fire-box, as shown.

The crown-plates 10 and 11 of the inner and outer shells 1 and 2 are vertically spaced, and one or more rows of vertically disposed fire-tubes 12 connect such plates, preferably adjacent to their outer edges, and 75 open communication between the interior of the fire-box and the atmosphere.

Disposed within the fire-box are one or more rows of upright water-tubes 13, which rise from the ledge 5, through which they 80 have communication with the base portion of the water-leg 4, and extend at their upper ends through the crown-plate 10 into communication with the upper portion of the water chamber, or the space between the 85 plates 10 and 11. These tubes are slightly inwardly inclined from their lower ends upwardly to enable them to communicate with the upper water space of the boiler within the row or rows of fire-tubes 12. The rows 90 of water-tubes 13 preferably extend entirely around the inner marginal portion of the fire-box, except for the space in register with the fire-door 14, and coöperate to form an interior fire-chamber. The tubes are prefer- 95 ably arranged in staggered relation to baffle the flames and highly heated products of combustion as they pass between and around the same to find an exit from the fire-box through the fire-tubes 12, which, as will be 100 noted, are disposed without the upper ends of the water-tubes. The water-leg 4 is provided immediately above the fire-door 14 with an inwardly projecting water-pocket 15, which is formed by a casting or member 105 16 secured to the edges of an opening 17 in the shell 1, and opening communication between the top of this pocket and the upper water space of the boiler are a plurality of short water tubes 18. It is thus evident 110 that the water-tubes 13 and 18 coöperate to entirely surround the upper central por-

tion of the fire chamber and that the space adjacent to and below the fire-door 14 is not obstructed by water-tubes.

A steam-dome 19 is mounted centrally on the outer crown-plate 11 within the set of fire-tubes 12, and has communication with the upper water space of the boiler through an opening 20 in the crown plate. If the steam-dome 19 is omitted the fire-tubes 12 will project through the steam space of the boiler and serve to superheat the steam.

It is found in practice that this form of boiler is inexpensive and comparatively light in construction, is highly efficient for the heating of water, and is economical in use of fuel, the arrangement of the fire and water tubes and the general construction of the boiler being such as to secure practically the maximum efficiency of the products of combustion generated therein.

I wish it understood that my invention is not limited to any specific construction, arrangement, size or shape of the parts, as it is capable of numerous modifications without departing from the spirit thereof.

Having thus described my invention, what I claim as new, and desire to secure by Letters Patent, is,—

1. In a boiler, inner and outer shells forming an interior fire chamber, an overhead water space, a water leg and an enlargement at the lower end of the water leg, a closed steam dome mounted on the top of the outer shell in communication at its bottom with said overhead water space, water tubes extending upward through the fire chamber and opening communication between said

water leg enlargement and the overhead water space, said water tubes being arranged in a circular set and inwardly inclined from their lower ends upwardly, fire tubes extending upward through the overhead water space and opening communication between the fire chamber without the upper ends of the water tubes, and the atmosphere around said steam dome, substantially as described.

2. In a boiler, inner and outer shells forming side upper and lower water spaces, a fire chamber, a door opening in the side of said chamber and an inwardly extending water pocket above the door in communication with the side water space, a steam dome on the top of the outer shell being of smaller diameter than the outer shell, a set of fire tubes extending from the outer upper portion of the fire chamber through the upper water space to the atmosphere around said dome, a set of long water tubes extending upward on an inward incline from the lower portion of the side water space to the upper water space, and a set of short water tubes extending upward on an inward incline from said water pocket to the upper water space, said long and short tubes having their upper ends communicating with the upper water space at points located within the set of water tubes, substantially as described.

In testimony whereof, I have hereunto signed my name to this specification in the presence of two subscribing witnesses.

THOMAS J. SHEA.
